UNITED STATES PATENT OFFICE.

JOHN L. BOGERT, OF NEW YORK, N. Y.

CRANK-AXLE LATHE.

No. 836,360.

Specification of Letters Patent.

Patented Nov. 20, 1906.

Application filed September 9, 1904. Serial No. 223,904.

To all whom it may concern:

Be it known that I, JOHN L. BOGERT, a citizen of the United States, and a resident of New York city, borough of Queens, State of New York, have invented certain new and useful Improvements in Crank-Axle Lathes, of which the following is a specification.

In United States Letters Patent No. 568,063, granted to me September 22, 1896, I have shown a lathe in which the crank-pin and the main portions of the crank axle or shaft may be readily turned or cut by shifting the position of the pin or shaft-bearings with respect to the axial line of the head-stock spindle.

My present invention relates to the class of machines shown in my said patent and provides means whereby a plurality of crank-pins or a plurality of bearing-surfaces of a multiple-throw crank axle or shaft may be simultaneously turned or milled and wherein by a simple adjustment of the crank-shaft one or the other set of pins or the main shaft-bearings may be adjusted in alinement with the head-stock spindles.

In carrying out my invention I provide two head-stocks, each having a spindle with gearing connecting said spindles so that they will rotate in absolute synchronism, and I provide each head-stock with a chuck adapted to grasp the end of a crank-shaft either eccentrically, so that the crank-pins may be brought into alinement with the axes of rotation of the head-stock spindles or concentrically with such spindles, so that the main bearings of the shaft may be alined with the axes of rotation of said spindles, and I also provide two carriages fitted on the ways of the bed for adjustment along the same.

Each carriage is provided with two cross-slides, gearing being provided for simultaneously causing the cross-slides of each carriage to be fed toward each other, whereby two tools may be caused to operate simultaneously on a crank-pin or main bearing-surface, two crank-pins or bearing-surfaces thereby being simultaneously turned or cut, or, as hereinafter shown, one cross-slide of a pair may carry a tool or mill and the corresponding cross-slide of such pair may carry an opposed thrust-bearing or supporting-surface to resist the transverse strain on the work. By thus having two carriages each provided with two cross-slides, each cross-slide being capable of carrying one or more tools and both ends of the shaft being driven,

it is possible to remove twice as much metal in the same space of time as can be done with a single carriage and single cross-slide thereon as in my said patent, whereby economy in turning the crank-pins and bearing-surfaces on multiple-throw crank axles or shafts is effected.

In this invention I also provide improved means for holding the ends of crank-shafts upon the head-stock spindles, whereby the position of the shaft or axle to be turned with respect to the axial line of the head-stock spindles may be quickly and accurately adjusted without removing the crank axle or shaft from the head-stock chucks.

My invention further comprises the novel details of improvement that will be more fully hereinafter set forth and then pointed out in the claims.

Reference is to be had to the accompanying drawings, forming part hereof, wherein— Figure 1 is a side elevation, partly in section, of a crank-axle lathe embodying my invention. Fig. 2 is an enlarged detail face view of the head-stock chuck. Fig. 3 is an edge view thereof looking from the left in Fig. 2. Fig. 4 is a vertical cross-section through the head-stock, substantially on the line 4 4 in Fig. 1. Fig. 5 is a cross-section, part being removed, through the main bed and head-stock on the line 5 5 in Fig. 1. Fig. 6 is an enlarged detail section through the end of the main driving-shaft and head-stock. Fig. 7 is a vertical cross-section, substantially on the line 7 7 in Fig. 1, looking in the direction of the arrows; and Fig. 8 is a plan view of a pair of cross-slides on a carriage, corresponding to that shown in Fig. 7.

Similar numerals of reference indicate corresponding parts in the several views.

The numeral 1 indicates the main bed of the machine, and 2 represents the ways, which may be of any well-known construction.

3 3^a are two head-stocks mounted upon ways 2 and similarly constructed, excepting that head-stock 3 is adapted to be adjusted along the ways, while head-stock 3^a will preferably be held fixed by means of bolts 2^a in well-known manner. The spindles 4 4^a of said head-stocks are to be rotated in absolute synchronism, and for this purpose they are provided with gear-wheels 5 5^a, that mesh with pinions 6 6^a, driven by main shaft 7, mounted in bearings in the main bed, and provided with pulleys 8 in well-known man-

ner. As the head-stock 3 is adjustable along the ways 2, I provide the pinion 6 with a hub 6^b, adapted to slide along shaft 7, a key 9 connecting the pinion and shaft, and at 10 is 5 a locking-nut on the hub 6^b, bearing against a shoulder 11 on the head-stock. To keep the ends of the head-stocks from rising from the bed and to compensate for wear, I provide a bearing for each of the pinions 6 and 6^a, 10 as follows: A semicircular bearing-surface 12 on the head-stock receives the hub 6^b and a cap or yoke 13 incloses the lower portion of hub 6^b and bears at its edges 12^a against ways 14 on bed 1, bolts 15 locking the caps 13 in 15 place and holding the surface 12^a and 14 in firm position. Thus as wear takes place within the bearing of shaft 7 on hub 6^b and along the surface 14 the wear may be taken up by the cap 13 and bolts 15, and thus 20 proper alinement of the head-stock is provided and the end of the head-stock is kept from rising. At the opposite end of the head-stock I provide a bearing 16, through which shaft 7 freely passes, (see Fig. 5,) 25 which bearing is secured to the head-stock by screws or bolts 17 and is provided with guiding-flanges 18, which engage ways 14 on bed 1 and prevent the head-stock from rising. As head-stock 3 is adjustable, the bolts 17 30 may be carried up in convenient position for access, as at the right in Fig. 1.

The spindles 4 4^a of the head-stocks are provided with means for gripping the ends of the crank-shaft 20 for holding said ends 35 either concentric with the axes of said spindles or eccentric thereto a distance equal to the eccentricity of the axial line of the crank-pins 20^a to be turned. In the arrangement illustrated the spindles 4 4^a have hubs 4^b, to 40 which chuck members 21 are eccentrically connected and adapted to firmly hold the ends of shaft 20. As shown, the member 21 is detachably connected with the hub 4^b, and for this purpose I provide a plate 22, having 45 a recess in one face to receive the hub 4^b to prevent lateral displacement of plate 22, (see Fig. 1,) and the chuck member 21 is pivotally supported upon plate 22, as by a bolt 23. The member 21 has a jaw comprising a semi- 50 circular part 21^a and a removable part 21^b, held together by bolts 24, forming a chuck-jaw that is bored or shaped to receive the end of shaft 20 and adapted to firmly grasp the same, as at 21^c. The bore 21^c is in one position located concentrically with respect to the axes of rotation of spindles 4 4^a; but by 55 moving the member 21 on its pivotal point 23 the bore 21^c may be adjusted to a position eccentric to the axis of the spindle and on a 60 radius described around the axis of pivot 23. By this means the members 21 may be adjusted laterally, so that the main part of shaft 20 may be sufficiently eccentric to the 65 axes of the spindles to bring the axis of rotation of the pins 20^a to be turned in alinement

with the axis of rotation of the spindles. I have shown the member 21, provided with a slot 21^d, engaging a locking-bolt 25, carried by plate 22 for holding the member 21 in any desired position of adjustment. The member 21 and plate 22 may have holes 26 to receive a pin, which holes may be at certain distances apart, whereby to indicate readily the amount of eccentricity of the bore 21^c of member 21 when the same is adjusted. 70 Parts 4^b and 22 may be detachably held together by bolts 22^a and dowel-pins 22^b. 75

From the foregoing it will be understood that when the ends of shaft 20 are secured in the bores 21^c of members 21 and adjusted to 80 a position concentric with the axes of rotation of spindles 4 and 4^a the main bearing parts of the crank-axle or shaft 20 will be in position to be turned, and that when the members 21 are moved sidewise until the 85 axes of crank-pins 20^a are brought into alinement with the spindles 4 4^a said crank-pins will be in the proper position for turning their surfaces to the desired diameters, and this without removing the shaft from its 90 chucks. So far, however, as my improvements in the means I have shown for causing the tools to cut the crank-pins and shaft-bearings are concerned the ends of the shaft may be connected with the spindles 4 4^a in 95 any usual or well-known manner by any suitable chucks.

The means I have shown for turning the crank-pins and shaft-bearings are as follows: 30 30^a are carriages mounted upon the ways 2 100 of bed 1 for adjustment along the same in any well-known manner, or as shown in my said Patent No. 568,063, and upon each carriage are mounted two cross-slides similarly constructed, and therefore a description of 105 one will apply to both. The pairs of cross-slides 31 32 are guided upon the corresponding carriage in well-known manner, and the cross-slides of each pair are fed toward and from each other simultaneously. To this 110 end I have shown the cross feed-screw 33, provided with right and left hand threads 34 35, meshing with corresponding nuts carried by the cross-slides, any suitable well-known means being provided for operating shaft 33. 115 At 36 is a shaft running along bed 1, and by means of usual or suitable gearing, such as shown in said Patent No. 568,063, operates the screws 33. A pair of frictions operated by a shaft 37 in well-known manner serves to 120 regulate the feeding to the cross-slides. Gearing 38 39 40, connecting shaft 36 with spindle 4^a, serves to impart proper speed of rotation to shaft 36. The cross-slides 31 32 are curved on their inner faces, as shown in 125 Figs. 7 and 8, to permit the full swing of the crank-arms 20^b during the feeding of the cross-slide, and said slides also have on one side relatively thin plates or supports 31^a 32^a, adapted to pass freely between the pairs

of crank-arms 20^b, so that the latter may straddle said plates or supports as they rotate.

At 41 is indicated a tool, shown in the form of a mill, having a plurality of cutting edges along its front face and corresponding cutting edges on opposite sides, and the front face of said mill is shown located at an angle with respect to the axis of the crank-pin or shaft-bearing. (See Fig. 7.) The tool 41 is shown carried upon a supporting-block 42, secured to the plate or support 32^a by bolts 43. If preferred, however, a tool having a single cutting edge (indicated at 44) may be provided in place of the milling-tool 41. To resist transverse cutting strains, each cross-slide may be provided with a tool which on one cross-slide should be diametrically opposed to the tool on the corresponding cross-slide of a pair, or instead of an extra tool on one cross-slide of a pair a rest or abutment may be provided thereon, as indicated at 45 46.

Referring to Fig. 8, both sets of cross-slides are represented, in which the pair nearest in view are provided, respectively, with the tool 41 and rest 45, and the cross-slides beyond respectively have the tool 44 and rest 46. It will also be understood that, if desired, each cross-slide may have two tools arranged at an angle of ninety degrees to each other, whereby in such case there would be four tools on a pair of cross-slides, thus presenting resistance to transverse strain, or there can be an opposed tool and support, as in Fig. 8, on two slides, and on the same two slides two other opposed tools and supports corresponding to tool 41 and support 45, or tool 44 and support 46. In either case cross-feed-threads 34 35 are such that the opposed cross-slides will be fed toward each other at absolutely equal speeds, whereby as the stock is cut away by one or more tools the torsional and transverse strains can be balanced or nearly balanced, so that by having two mills or cutting-tools secured to the two opposed cross-slides and by feeding them against the work from opposite sides simultaneously rapidity and accuracy of turning the work can be effected. As I have provided two carriages, each of which carries two cross-slides constructed and operating as set forth, four mills or cutting-tools may be simultaneously operating in pairs on any two bearing-surfaces or crank-pins that are in axial alinement with the center of rotation of head-stock spindles 4 and 4^a. Thus, as both ends of the shaft are driven and as the work is backed up by a tool or rest, it is possible to remove twice as much metal by the cutting-tool without increasing the torsional strain on the crank-shaft, as would be the case with only one end of the shaft being driven. By operating two or more tools on two opposed cross-slides and by having two

pairs of such cross-slides and tools simultaneously operating two crank-pins or two bearing-surfaces may be simultaneously cut to the required diameter, and as the mills 41 have cutting edges on the sides the inner opposed faces of two crank-arms can be cut while cutting the corresponding crank-pins to the required diameter. It will thus be apparent that by means of my improvements I am enabled to quickly, economically, and accurately cut or turn multiple-throw crank arms, pins, and bearings, and this while requiring but a relatively small amount of adjustment of the crank-shaft with respect to its supporting-spindles.

The details of construction shown and described and the character of the gearing and other well-known mechanical devices used in the lathe may be varied or used, as deemed desirable, without departing from the spirit of my invention.

Having now described my invention, what I claim is—

1. In a lathe, the combination of a pair of head-stocks provided with spindles, means for driving said spindles at the same speed and in the same direction, means for securing the ends of a crank-shaft to said spindles, a pair of carriages located between said head-stocks, a pair of slides carried by each carriage, means for simultaneously feeding the slides of each pair toward each other, and means for securing a cutter or rest to said slides, substantially as described.

2. In a lathe, the combination of a pair of head-stocks provided with spindles, gearing for operating said spindles at the same speed in the same direction, means for adjusting one of said head-stocks toward and from the other and for coincidentally adjusting part of said gearing, means for securing the ends of crank-shafts to said spindles, a pair of carriages located between said head-stocks, a pair of slides carried by each carriage, means for feeding the slides of each pair toward each other at the same speed, and means for supporting tools or rests upon said slides, substantially as described.

3. In a lathe, the combination of a pair of head-stocks provided with spindles, means for driving said spindles at the same speed and in the same direction, means for securing the ends of a crank-shaft to said spindles, a pair of carriages located between said head-stocks, a pair of slides carried by each carriage, means for feeding the slides of both pairs simultaneously toward the working point, and means for supporting tools or rests upon such slides, substantially as described.

4. A chuck of the character described comprising a support, a member eccentrically pivotally connected therewith, said member having means for gripping the end of a crank-shaft, and means for holding said member in

position to bring the crank-shaft or its crank-pins concentric with the axis of rotation of said support, substantially as described.

5. A chuck of the character described comprising a spindle, a member eccentrically pivotally connected therewith to be rotated thereby, said member having a movable piece and means to cause it to grip a crank-shaft, and means for holding said member in 10 different positions of adjustment to bring the crank-shaft or its crank-pin in alinement with the axis of rotation of said spindle, substantially as described.

6. A chuck of the character described comprising a spindle provided with a hub, a plate removably connected with said hub, a member eccentrically pivotally connected with said plate, said member being provided with means for holding a shaft, and means for 15 holding said member in different positions of adjustment, substantially as described.

7. A chuck of the character described comprising a spindle, a support connected therewith, a member eccentrically pivotally connected with said support, said member having a curved edge, a cap to fit over said edge, means for clamping said cap upon a shaft, and means for holding said member in different positions of adjustment, substantially as 20 described.

8. In a lathe, the combination of a bed having ways, a head-stock provided with a

bearing portion between said ways, a shaft entering said bearing portion, gear connection between the shaft and the spindle in the head-stock, and a cap having upturned bearing edges adapted to engage said ways, with means for securing said cap to said head-stock, whereby the head-stock is kept from rising from the bed, substantially as described.

9. In a lathe, the combination of a bed provided with ways, a driving-shaft, a head-stock, gearing between said shaft and the spindle in the head-stock, a bearing portion 45 receiving said shaft and provided with guiding-flanges engaging said ways, and means for connecting said bearing with said head-stock, substantially as described.

10. In a lathe, the combination of a pair of 50 head-stocks provided with spindles, means for driving said spindles in the same direction and at the same speed, means for securing a crank-shaft to said spindles, a pair of carriages located between said head-stocks, 55 means for supporting a tool on one carriage on one side of the work, means for supporting a tool on the other carriage on the opposite side of the work, and means for feeding said tools to the work.

JOHN L. BOGERT.
